US00D685756S

(12) **United States Design Patent**
Liu

(10) **Patent No.:** **US D685,756 S**
(45) **Date of Patent:** **** Jul. 9, 2013**

(54) **TRANSMITTER**

(71) Applicant: **Shenzhen Aetertek Technology Co., Ltd.**, Guangdong (CN)

(72) Inventor: **Yunbing Liu**, Guangdong (CN)

(73) Assignee: **Shenzhen Aetertek Technology Co., Ltd.**, Shenzhen (CN)

(**) Term: **14 Years**

(21) Appl. No.: **29/444,625**

(22) Filed: **Feb. 1, 2013**

(51) **LOC (9) Cl.** **14-03**

(52) **U.S. Cl.**

USPC **D14/155**

(58) **Field of Classification Search**

USPC D14/167, 154, 168, 188, 496, 156, D14/160, 161, 162, 163, 164, 165, 158, 341, D14/346, 342, 345, 137, 155, 218, 225; D16/208; D26/38; 455/351, 350; D10/104.1, D10/106, 65
